AUDIBLE SIGNAL FOR PLANT SOIL CONDITIONS

Bjorn N. De Bough, 801 1st NE., Seattle, Wash., and
Robert D. Swenson, Seattle, Wash.; said Swenson as-
signor to said De Bough

Filed July 8, 1974, Ser. No. 486,333

Term of patent 14 years

Int. Cl. D10—06

U.S. Cl. D10—116

FIG. 1 is a side elevational view of an audible signal for plant soil conditions showing my new design;

FIG. 2 is a front elevational view;

FIG. 3 is a rear elevational view;

FIG. 4 is a top plan view; and

FIG. 5 is a bottom plan view thereof.

We claim:

The ornamental design for an audible signal for plant soil conditions, as shown and described.
